UNITED STATES PATENT OFFICE.

FREDERICK MEYER, OF NEWARK, NEW JERSEY.

IMPROVEMENT IN MACHINES FOR FORMING SCALE-PANS.

Specification forming part of Letters Patent No. 122,045, dated December 19, 1871.

To all whom it may concern:

Be it known that I, FREDERICK MEYER, of the city of Newark, in the county of Essex and State of New Jersey, have invented a new and useful Machine for Making Seamless Scoops for Scales, of which the following is a specification :

In the accompanying drawing, Figure 1 is a front elevation of machine for producing seamless scoops. Fig. 2 is a cross-section in line $\alpha\alpha'$, of Fig. 1. Fig. 3 is a similar view, the top or convex roller being removed. Fig. 4 is a plan or top view of the machine, and Fig. 5 is a detached perspective view of the forming-die, located between the rolls.

My invention consists of the combination of a fixed forming-die with revolving forming-rolls of a rolling-machine, which die fills up the space between said rollers, leaving only sufficient room for the sheet metal to pass between them and the two concave rollers, and a continuous bed or die for the correspondingly-shaped convex upper roller to move on. The said die and rollers are shaped to correspond to the shape of the scoops of weighing-scales desired to be produced seamless.

In the accompanying drawing I have shown the rollers and die shaped so as to produce seamless scoops for ordinary scales. Between the upright $A A'$ of a suitable frame, which may be held to each other by cross-rods or bars B , are located rollers $C D E$, the lower concave roller C and the upper convex roller E having their bearings in suitable boxes, sliding in vertical slots $a a'$ formed in the uprights $A A'$, while the upper concave roller D has its bearings in boxes sliding in horizontal slots d in the rear extensions $F F'$ of the uprights $A A'$. The shafts of the rollers $C D E$ carry, on the outside of upright A' , cog-wheels G , which gear with each other, and thus motion is transmitted to the rollers $D C$ through the operation of roller E , the shaft of which, outside the upright A , may carry a hand-crank, H , or any other suitable means to give it motion. Between the bearing-boxes of the rollers C and E are placed springs to allow elasticity to the rollers, which may be regulated by set-screws f passing through caps g over the slots $a a'$ in the uprights $A A'$; the set-screws h , passing through caps i over the slots d , serve to adjust the roller D . By removing these caps g in

the rollers and their bearings may be removed. In Fig. 5 I have shown a detached view of the die J , which has a concave face, j' , which corresponds with the concavity of the rollers $D C$, and the face j corresponds with the convex surface of roller E . The sides of this die having a certain degree of concavity allow the die to be held suspended between the rollers $D C$ without any other means of support, while at the same time these rollers are free to revolve without binding. The face j of the die, extending the entire length of the rollers and its edges resting in their concavity, forms with them a continuous concave surface, over which the piece of sheet metal, which has previously received an oval or other appropriate circumference, passes, and against which this piece of sheet metal is pressed into scoop-shape by means of the convex roller E . Were the die J not used, the edge of the piece of sheet metal would either pass under the roller D instead of over, and thus no curve in the cross-section of the scoop would be produced, or, in case it did pass over the roller D , that part of the sheet metal passing over the space between the rollers D and C would be liable to be sunk into said space, and thus disfigure or wrinkle up the scoop. But as by using the die J every particle of the piece of sheet metal during its entire passage through the rollers is held between solid surfaces, it is not only impossible for any portion of the scoop to be imperfect, but no hand labor is at all required to finish the scoop after it comes from the rollers. The die J , as well as the rollers $C D E$, may be made in sets of different sizes to produce different-sized scoops for scales, and are preferably constructed of steel. The entire machine occupies but very little space, is simple in construction, and easy to manipulate, and as the die is perfectly loose and only held suspended between the rollers $D C$ no adjustment or fastening and loosening is required. The blanks for the scoops may be prepared in oval or other suitable shape, in large numbers, by cutting or stamping them out, and thin scoops produced by merely passing these blanks through between the rollers in continuous succession as fast as the rollers can be turned.

Having described my invention, I claim—
1. In combination with revolving forming-rolls

of a rolling-machine, a fixed forming-die, located and operating substantially as described.

2. A die, J, shaped to correspond to the shape of the rollers of a rolling-machine, and located between the rolls in such a manner as to fill the space between the three rolls so as to allow a piece of sheet metal to be passed between the rolls, as described.

The above specification of my improved machine for making seamless scoops for scales, signed this 27th day of October, 1871.

FREDERICK MEYER.
